DEHYDRATION OF NORMALLY GASEOUS HYDROCARBONS

Robert Pyzel, New York, N. Y., and Clarence G. Gerhold, Chicago, Ill., assignors to Universal Oil Products Company, Chicago, Ill., a corporation of Delaware

Application July 31, 1941, Serial No. 404,890

4 Claims. (Cl. 202—42)

This invention relates particularly to the dehydration of propane and butanes though the process disclosed may also be applied to dehydration of ethane or heavier vaporizable paraffins. The present application is a continuation-in-part of our copending application Serial No. 232,571, filed September 30, 1938.

The invention is more specifically concerned with a method for dehydrating butanes which are to be subjected to dehydrogenation in contact with special types of metal oxide catalysts to produce high yields of the corresponding olefins therefrom. It is in most cases partly essential to keep the water vapor content of paraffinic gas mixtures undergoing catalytic dehydrogenation at a minimum figure since if appreciable amounts of water vapor are present the life of the catalyst is adversely affected.

While the olefinic constituents of the gaseous by-products of oil cracking operations are being extensively utilized for the production of additional yields of good antiknock gasoline by both thermal and thermal-catalytic methods, the utilization of the residual paraffins which are not readily convertible into motor fuel products without the use of extreme conditions of temperature, pressure, and time, has lagged considerably. Obviously if efficient processes are available for converting gas mixtures such as propane and the butanes into the corresponding mono-olefins, the utilization of cracked gas mixtures and natural gases would be materially simplified and the yield of polymer gasoline or other product would be materially increased. The present process is concerned with means for accomplishing this end.

In one specific embodiment the present invention comprises a process for dehydrating paraffin hydrocarbons capable of forming constant-boiling azeotropes with water which consists in introducing the water-containing liquid hydrocarbon to a settling zone in which water is separated and removed, subjecting the supernatant hydrocarbon liquid to distillation to produce overhead vapors containing proportionately more water than the residual liquid from the fractionation, condensing the vapor mixture in the fractionating zone and introducing the condensed hydrocarbons and water to the settling zone, and recovering dehydrated hydrocarbon from the fractionating zone.

The outline of the process as given in the preceding paragraph will be amplified to indicate its important features in greater detail by describing characteristic operations in connection with the attached diagrammatic drawing which shows in

general side elevation an arrangement of apparatus in which the process may be conducted. The drawing is not to any absolute or relative scale and the design and relative sizes of individual units may be varied within reasonable wide ranges without departing from the scope of the invention.

Referring to the drawing paraffinic hydrocarbons such as for example propane or butane which require preliminary treatment for the removal of sulfur or other compounds deleterious to the dehydrogenating catalyst, may be introduced to the plant through line 1 containing valve 2 to a circulating pump 3 which discharges through a filled or packed column mixer 4 leading to settling tank 5. Aqueous treating solutions are introduced through line 8 containing valve 9 to pump 10 which discharges through line 11 containing valve 12 into line 6, which constitutes a recirculating line from a settling tank back to the circulating pump and is controlled by valve 1. A definite amount of washing solution is ultimately wasted through line 13 and valve 14 to make up for the amount introduced through line 8.

The solutions employed for washing the material introduced (which is preferably under sufficient pressure to maintain it in liquid phase) consists generally of weak aqueous acids or alkalies depending upon the nature of the impurities present which may later affect the life of the dehydrogenating catalyst or catalysts used in subsequent processing. Raw paraffinic gases or fractions thereof frequently contain hydrogen sulfide, mercaptans, ammonia, and amines. Hydrogen sulfide and methyl mercaptan are removable by the use of caustic soda solutions and the alkaline impurities comprising ammonia and amines may be washed out by water or very weak acids. The choice of a wash liquid will depend to a large extent on the nature of the impurities in the charge. If desired both acid and alkaline solutions may be used if beneficial results are obtained.

The treated material from the upper portion of the settling tank passes through line 15 containing valve 16 to a receiver 17 which has a vent line 18 containing a valve 19 for the removal of incidental accumulations of fixed gases and a drain 20 containing a valve 21 for the removal of aqueous layer. Receiver 17 is preferably tilted so that the water drain 20 is at the lowest position and vent line 18 is at the highest point. Wet liquid hydrocarbon passes through line 22 containing valve 23 to a pump 24 which discharges by way of line 25 containing valve 26 to a de-

hydrator 27, which is essentially a fractionating column of a design capable of effecting an azeotropic distillation. This dehydrator is preferably operated at a temperature but a few degrees above the boiling point of the hydrocarbon charged, utilizing for this purpose a lower section heating coil 32 which may be heated by exhaust steam introduced through line 28 containing valve 29 and vented through line 30 containing upstream pressure control valve 31. The principle upon which the dehydrator operates is the distillation of an azeotropic mixture of hydrocarbon and water which contains proportionately more water than that dissolved in the hydrocarbon charged. The mixture of water vapor and hydrocarbon vapor passes through line 33 containing up-stream pressure control valve 34 at a pressure of approximately 100 lbs., per square inch (in the case of butane; higher in the case of propane) and is condensed during passage through condenser 34' after which the condensed material flows to receiver 17, the excess of water over that soluble in the hydrocarbon appearing as a lower layer and being drawn off through the water drain. The maintenance of approximately a 1:1 recycle ratio in the dehydrator is usually sufficient to insure the dehydration of the charge to a point consistent with the maintenance of the activity of the dehydrogenating catalyst encountered later in the process.

The dehydrated hydrocarbon leaves dehydrator 27 through line 35 containing valve 36, passes through a cooler 37 and follows line 38 to pump 39 which in turn discharges through line 40 containing valve 41 to a catalytic dehydrogenating unit.

A catalyst frequently employed in dehydrogenating processes is of a special character which has been found to be highly efficient in dehydrogenating paraffin hydrocarbons to produce mono-olefins and di-olefins therefrom. It consists in general of granular or pilled particles of specially prepared and activated alumina supporting minor proportions of chromium sesquioxide. For the purposes of the present invention the molecular percentage of chromium sesquioxide referred to alumina is 20 or lower and good results are usually obtainable when employing alumina supporting between 8 and 16% by weight of the chromium oxide. Catalysts of this character may be prepared by adding ammonium chromate or chromic acid to activated alumina granules and then calcining at a moderate temperature to drive off water or basic radicals leaving a deposit of the trioxide, Cr_2O_3 . The trioxide is then reduced in a stream of hydrogen or other reducing gas until substantially completely reduced to the sesquioxide, which is evidently the effective dehydrogenating catalytic material.

While alumina-chromia catalyst has been found to be very effective in dehydrogenating paraffinic gases, the dehydrogenating process itself is not necessarily limited to the use of this particular catalyst, but may employ other composite catalysts such as, for example, those consisting of other inert refractory carriers than alumina supporting other compounds or oxides than chromium sesquioxide which have a definite and selective dehydrogenating activity. As representative of other inert carriers which may be employed may be mentioned magnesium oxide; certain types of clays, such as those of a bentonite or montmorillonite variety, either raw or acid treated; fuller's earth; firebrick; crushed silica; and glauconite. Other compounds which have

dehydrogenating activity may comprise, for example, the oxides of other metals in the left-hand column of group VI of the periodic table along with chromium, including molybdenum, tungsten, and uranium, although the last named may not be utilizable in practice on account of its rarity and high cost. Other elements the compounds of which, and particularly the oxides, may be employed are the elements in the left-hand columns of groups IV and V of the periodic table, comprising titanium, zirconium, cerium, hafnium, and thorium, vanadium, columbium, and tantalum. The catalysts which are alternatively utilizable are not exactly equivalent in their action and are not to be considered as absolute substitutes one for the other. This fact will be more or less apparent to those conversant with the practical aspects of catalysis.

The following general example is introduced to indicate the character of the results obtainable in practice of the invention although not with the intention of unduly circumscribing its proper scope.

A n-butane fraction obtained from cracked gases was charged to the plant and thoroughly washed with 10° Bé. caustic soda for the removal of sulphur compounds. This material was then passed through the dehydrating unit as described in connection with the drawing and distilled under a pressure of 100 lbs., per square inch with a bottom temperature of about 150° F., a 1:1 recycle ratio effecting dehydration of the material to less than .08% water by weight.

The preliminarily treated and dehydrated normal butane fraction could then be dehydrogenated in contact with an alumina-chromia catalyst and a temperature of 1050° F. to yield 31% butenes per pass and ultimate yields of 90% butenes.

40 We claim as our invention:

1. A method for separating water from a mixture thereof with liquefied normally gaseous paraffin hydrocarbons, which comprises introducing the water-containing hydrocarbon liquid to a settling zone and therein separating water from hydrocarbons, removing wet hydrocarbon liquid from said zone and introducing the same to a dehydrating zone, vaporizing from the liquid in the dehydrating zone a mixture of hydrocarbons and water containing proportionately more water than the liquid charged to the dehydrating zone, condensing the vapor mixture from the dehydrating zone and introducing the condensed hydrocarbons and water to the settling zone, and removing dehydrated hydrocarbon liquid from the dehydrating zone.

2. In the purification of normally gaseous paraffin hydrocarbons by treatment thereof in liquid phase with aqueous refining agents, whereby water is commingled with the hydrocarbons, the method of dehydrating the refined liquefied gas which comprises introducing the water-containing liquefied gas to a settling zone and therein separating water from hydrocarbons, removing wet hydrocarbon liquid from said zone and introducing the same to a dehydrating zone, vaporizing from the liquid in the dehydrating zone a mixture of hydrocarbons and water containing proportionately more water than the liquid charged to the dehydrating zone, condensing the vapor mixture from the dehydrating zone and introducing the condensed hydrocarbons and water to the settling zone, and removing dehydrated hydrocarbon liquid from the dehydrating zone.

3. A method for dehydrating a liquid mixture

containing paraffin hydrocarbons and water which comprises introducing the water-containing hydrocarbon liquid to a settling zone and therein separating water from hydrocarbons, removing wet hydrocarbon liquid from said zone and introducing the same to a dehydrating zone, vaporizing from the liquid in the dehydrating zone a mixture of hydrocarbons and water containing proportionately more water than the liquid charged to the dehydrating zone, condensing the vapor mixture from the dehydrating zone and introducing the condensed hydrocarbons and water to the settling zone, and removing dehydrated hydrocarbon liquid from the dehydrating zone.

4. In the purification of paraffin hydrocarbons by liquid phase treatment thereof with aqueous refining agents, whereby water is commingled

5 with the hydrocarbons, the method of dehydrating the refined hydrocarbons which comprises introducing the water-containing hydrocarbon liquid to a settling zone and therein separating water from hydrocarbons, removing wet hydrocarbon liquid from said zone and introducing the same to a dehydrating zone, vaporizing from the liquid in the dehydrating zone a mixture of hydrocarbons and water containing proportionately more water than the liquid charged to the dehydrating zone, condensing the vapor mixture from the dehydrating zone and introducing the condensed hydrocarbons and water to the settling zone, and removing dehydrated hydrocarbon liquid from the dehydrating zone.
